DAM CONSTRUCTION

Filed Jan. 27, 1930

FIG. 1

FIG. 2

FIG. 3

UNITED STATES PATENT OFFICE

KIDDSON L. KIDD, OF ARCADIA, CALIFORNIA

DAM CONSTRUCTION

Application filed January 27, 1930. Serial No. 423,810.

This invention relates to dam constructions.

The general object of my invention is to provide a flexible dam.

5 A further object of the invention is to provide a dam construction which will withstand earthquake shocks and undermining.

An additional object of the invention is to provide a dam constructed of a plurality of independent units.

A specific object of the invention is to provide a dam constructed of a plurality of independent initially hollow units.

Other objects of this invention will be apparent from the following description taken in connection with the accompanying drawings wherein:

Fig. 1 is a fragmentary top plan view of a dam constructed in accordance with my invention.

Fig. 2 is a section taken on line 2—2 of Fig. 1, showing a portion of the dam, and

Fig. 3 is a diagrammatic top plan view showing the manner of tying the various units together.

Referring to the drawings by reference characters I have indicated my improved dam generally at 10. As shown this dam is formed of a plurality of staggered rows of hollow cylinders or units 12 which are preferably made of concrete and are formed open at the top and are shown as provided with a bottom wall 13.

Within the units 12 I provide a plurality of hollow cylinders or units 14 which are also preferably made of concrete and are positioned to occupy as much of the space in the units 12 as possible. The space in the units 12 not occupied by the units 14 is filled by smaller units 14a and with any suitable material such as puddled clay as indicated at 15. The space within the units 14 and 14a I preferably fill with suitable material such as puddled clay as indicated at 16.

45 Between the units 12 I provide units or pipes 17 which are also preferably made of reinforced concrete and are adapted to occupy as much of the space between the units 12 as possible and the space therebetween not occupied by the units 17 I preferably fill

with a non-pervious material such as puddled clay as indicated at 18.

At the front and rear faces of the dam I have shown cylinders 19 which are of less diameter than the cylinders or units 12 which are also preferably made of concrete and are positioned partially between adjacent units to present a continuous concrete front on each face of the dam.

Across the dam between the adjacent rows of units 12 I preferably provide a flexible metal diaphragm 20 which may continue the full width and height of the dam and which is particularly adapted to prevent leakage of the stored water between the units 12. One or more diaphragms 20 may be used depending on the size of the dam.

The units 12 and 19 are preferably secured together by spaced bands 21 as shown diagrammatically in Fig. 3. As shown the cylinders 14 are secured together longitudinally of the dam by spaced metal bands or cables 22 and diagonally by similar bands 23 and 24. The arrows in Fig. 3 indicate the directions in which the bands shown tend to pull the cylinders or units.

The securing bands maintain the cylinders in correct position while allowing the units to slide along one another transversely or vertically.

In constructing a dam according to my invention it is desirable to excavate until the bedrock or other impervious footing is reached and then the units set or cast directly on the foundation, but if it is inconvenient to reach bedrock the dam may be placed on any suitable strata.

In a dam of this type the various elements are free to move vertically and more or less free to move laterally, so that earthquake tremors while they may rock the dam will not cause a break to occur therein.

On the top of the down stream portion of the dam I preferably provide an apron 25 which slopes from the highest portion of the dam to the lowest. The overflow water passes over the apron 25 and does not fall from one unit to the other, which would eventually wear the filling material out of the units and from between the units. The

apron 25 is preferably made of reenforced concrete and is provided with a manhole 26 having a cover 27 thereon, or a plurality of the same, so that any leakage of water past the apron may be allowed to drain off.

5. In large dams the space between the apron 25 and the units may be utilized as passageways for workers or even for pedestrians and vehicles.

10. It is intended that the width of the base shall be greater than the height of the structure and the faces of the dam being stepped down, or sloped, will give a diverted, or downward thrust to the weight of water superimposed upon it while the lower face forms a powerful brace against pressure.

15. The units may be of different shapes; they are here shown as cylindrical because of economy of construction and the round form 20 will allow more freedom of movement with less danger of fracture while requiring no more material than a much smaller solid type of dam.

25. It is now intended that construction of units and excavation proceed simultaneously, the excavated material being placed within the larger units while any of the smaller units desired are left unfilled as means of access to the footing of the dam for grouting or 30 any necessary work thereon.

35. While this dam is intended to be built in the usual arch shape it may be built in any other form by arranging groups of units to act as buttresses and curtains thereby permitting its construction in places where any other type of dam is feasible and even where no other is practicable.

40. From the foregoing description it will be apparent that I have provided a novel dam construction which is economical to construct and highly efficient in use.

45. What I claim is:

1. A dam construction comprising a plurality of rows of elongated members, said members being positioned in close proximity to each other, an impervious diaphragm extending across said dam between said members and means to band said members together.

50. 2. A dam construction comprising a plurality of rows of elongated members, said members being positioned in close proximity to each other, there being spaces between said members and a filling in said space, an 55 impervious diaphragm extending across said dam between adjacent rows of said members and means to bind said members together.

60. 3. A dam construction comprising a base, a plurality of rows of elongated members vertically arranged on said base, said members being positioned in close proximity to each other, a filling between said members, means to hold said members in assembled relation, said means allowing vertical and lateral movement between said members.

4. A dam construction comprising a plurality of elongated members, said members being positioned in close proximity to each other, there being a space between said members, the space between said members being filled, and means to band said members to allow vertical shifting relative to each other.

5. A dam construction comprising a plurality of rows of hollow members, said members being positioned in close proximity to each other, said hollow members having a filling therein, hollow members positioned between said first hollow members, said second hollow members being filled, the space between said first members not occupied by said second members being filled, an impervious diaphragm extending across said dam between adjacent rows of said first hollow members, said first members being banded together diagonally and lengthwise of said dam.

6. A dam construction comprising a plurality of rows of hollow members, said members being open at the top and closed at the bottom, said members being positioned in close proximity to each other, a plurality of hollow members in said first hollow members, said second hollow members being filled with a loose material, the space in said first hollow members not occupied by said second hollow members being filled, the space between said first members being filled, said first members being banded together.

7. A dam construction comprising a plurality of rows of hollow members, said members being positioned in close proximity to each other, a plurality of hollow members in said first hollow members, said second hollow members being filled with a loose material, the space in said first hollow members not occupied by said second hollow members being filled, hollow members positioned between said first members, said third hollow members being filled, the space between said first members not occupied by said third members being filled.

8. A dam construction comprising a plurality of rows of hollow members, said members being positioned in close proximity to each other, a plurality of hollow members in said first hollow members, said second hollow members being filled with suitable material, the space in said first hollow members not occupied by said second hollow members being filled, the space between said first members being filled, an impervious diaphragm extending across said dam between adjacent rows of first hollow members, said first members being banded together diagonally and lengthwise of said dam.

9. A dam construction comprising a plurality of rows of hollow members, said members being open at the top and closed at the bottom, said members being positioned in close proximity to each other, a plurality of

hollow members in said first hollow members,
said second hollow members being filled, the
space in said first members not occupied by
said second hollow members being filled, hol-
5 low members positioned between said first
hollow members, said third hollow members
being filled, the space between said first mem-
bers not occupied by said third members being
filled, said first members being banded to-
10 gether diagonally and lengthwise of said
dam.

In testimony whereof, I hereunto affix my
signature.
